ELECTRICAL MUSICAL INSTRUMENT

Laurens Hammond, Chicago, Ill.

Application April 7, 1941, Serial No. 387,113

5 Claims. (Cl. 84—1.01)

My invention relates generally to electrical musical instruments, and more particularly to instruments of the organ type particularly adapted for the accompaniment of multi-part harmony singing.

In the singing of four part harmony, such for example, as that rendered by choirs in the singing of hymns, and as would be desirable in the singing of hymns by a congregation, the singer must be very well trained in order to sing his part. In fact it is so difficult for the individual to sing only his part that it is well known that in congregational singing only a relatively small proportion of the congregation is able to carry any part other than the soprano, or the soprano melody an octave lower than it is scored.

The difficulty that singers of a congregation encounter in endeavoring to carry a part other than the soprano is likewise encountered by members of the choir, and even members of a quartet, requiring a great deal of practice and rehearsal on their part to acquire the ability to sing parts other than the melody part, usually the soprano.

As a result of this difficulty, congregational singing generally lacks the beauty of the four part harmony intended by the composer, and the individual singers fail to obtain the pleasure and satisfaction which would be theirs if they had the ability to sing the various harmony parts.

The accompaniment provided by an organ does not assist the congregation materially in singing the harmony parts since the over-all effect of the organ accompaniment on the listener is to bring out the melody rather than the harmonic accompaniment parts.

It has been proposed in the past to overcome these difficulties by using four separate organs, each with an organist playing but a single one of the four harmony parts. With the speakers of the four organs located each adjacent the appropriate section of the choir, the singers of each section would hear their parts much more predominantly than the other parts, and would thus be aided in singing the proper note. Such an arrangement, however, requires four separate consoles and requires a conductor for the four organists. Thus, it is not an arrangement which would be practical for use in the average church. Even in the few circumstances where such arrangement would not be prohibitively costly, it would not be as practical as an arrangement whereby a single organist could play

on a single console all four parts, with the tones of each part emanating from sound sources respectively located near the singers singing such parts.

It is thus the primary object of my invention to provide a plurality of musical tone producing devices which may be separated sufficiently apart to enable singers to hear the tones emanating from one device much more predominantly than the tones emanating from the other of such devices, and to provide a single console upon which multi-part harmony may be played, the console being one having electrical circuits under the control of its keys to cause the production of their respective harmony parts by the different tone producing devices.

Other objects will appear from the following description, reference being had to the accompanying drawings in which:

20 Figure 1 is a perspective view of the instrument illustrating the manner in which it is to be used;

Figure 2 is a wiring diagram of one form of the instrument;

25 Figure 3 is a perspective view of a preferred modification of the keyboard; and

Figure 4 is a wiring diagram of a preferred modification of the instrument.

30 Figure 5 is a wiring diagram of a preferred modification of the instrument.

The general principles of the invention are illustrated in Fig. 1 wherein an organist is shown seated at a console 60 having a keyboard 63, the console including a bass speaker 64 and a tenor speaker 66. These speakers may be permanently secured in the console or may be provided with suitable housings and extension cables, so that the speakers may be removed from the console and placed spaced distances from each other and from the console. A soprano speaker 68 is mounted upon a suitable floor stand 70 which is connected to the console 60 by a suitable shielded conductor 72, while an alto speaker 74 is mounted upon a similar floor stand 76 and connected to the console 60 by a shielded conductor 78.

35 The speakers 64, 66, 68 and 74 are located sufficiently far apart that singers for the various voices may group themselves about their respective speakers in the manner illustrated. The keyboard arrangement of the console is such that when four part harmony is played upon it, the tones of each part will be produced only by the speaker for such part. Under these circumstances each group of singers will be sufficiently

close to the speaker for the part which the group is singing that such group will hear its part predominantly over the tones produced by the speakers from which the other parts emanate.

As a result of this arrangement, the various singers are aided in singing their respective parts so that four part harmony music may be rendered effectively without the necessity of having very highly trained singers, and without requiring frequent rehearsals.

The speakers 64, 66, 68 and 74 are intended to be representative of any suitable musical tone producing devices capable of being controlled from the console 60. For facilitating installation in a church, the sound producing devices may be distributed throughout the congregation.

There are a number of characteristics of four part harmony music which apparently are peculiar to this type of music, particularly as represented by hymns:

(a) The tonal ranges of the four parts overlap each other. For example middle C (261.626 C. P. S.) may be scored to be sung by the bass, tenor, alto or soprano voice.

(b) The score never requires the alto to sing a note higher than that sung by the soprano, nor does the score ever require the bass to sing a note higher than that to be sung by the tenor. This is shown by the fact that musical notation does not provide any means for indicating a soprano note lower than a concurrent alto note, or a tenor note lower than a concurrent bass note. Similarly, the score never requires the alto to sing a note lower than that to be sung concurrently by the tenor.

(c) In hymns, all parts are usually scored to be sung simultaneously. It is seldom that one part only rests.

(d) The gamut of the combined voices does not exceed three octaves plus two semi-tones (F1-87.307 C. P. S. to G4-783.99 C. P. S.), i. e., a total of 38 semi-tones so that a keyboard of thirty-eight keys is sufficient for the rendition of practically all hymns as written.

These characteristics of four part harmony music, particularly hymns, lead one to the deduction that it would be mechanically possible to provide an electrical musical instrument, playable by a single player, with a keyboard switching mechanism so arranged that the tones of each of the four parts would be produced by a sound producing device individual to that part, and the primary objective of the invention thus achieved.

However, apparently insurmountable difficulties are introduced in devising a keyboard switching mechanism for such instrument because of the presence in hymns as scored, of a large number of unison notes, i. e. notes which should be sung by both the alto and soprano, or by both the tenor and the bass, or possibly both the alto and tenor. Because it is within the province of the hymn composer to decide which of three notes scored shall be sung in unison by two of the voices, (and no definite rule for deciding this appears to be followed), it is improbable that any switching mechanism for a standard keyboard could be devised which would always follow the composer's precept in this respect.

For example, the notes G2, B2, D3 may be scored in a manner to indicate (a) that the tenor and bass are to sing the note G2, alto B2 and soprano D3, or (b) that the bass is to sing note G2, tenor B2 and both alto and soprano are to sing the note D3, or (c) that the bass is to sing 75

note G2, both tenor and alto to sing B2 and soprano to sing D3. In playing these three notes on a standard keyboard three keys would be depressed, and it appears impossible that ϵ y switching mechanism, or means of any nature whatsoever, could be devised which could, merely by depression of the three keys, cause the proper notes to be sounded by the four individual sound producing devices, to follow the composer's precept as to which of the foregoing systems a, b or c should be followed in sounding these notes from the various sound producing devices.

However, the difficulties set forth in the two preceding paragraphs are not as serious as might at first appear because, in the first place, the mechanism may be designed to follow the system exemplified by only one of the systems a, b or c, preferably the system b, and secondly 10 no discords or lack of harmony would result even if the sound producing devices for the tenor and alto parts occasionally produced the tones of adjacent higher parts when it should have produced the tones of the adjacent lower part and vice versa.

The switching system of Fig. 2, while it is somewhat complicated, fulfills the necessary conditions of a two part harmony instrument completely, but as a system for producing four part harmony it has the disadvantage that it may, under some conditions, cause the tenor note to be sounded by the alto sound producing device and vice versa.

In Figure 2, representative keys of a keyboard 35 extending from the note C1 to G4 are shown, the keys being designated by reference characters corresponding to the notes. Four oscillators 84, 86, 88, and 90 of simple construction are shown for generating the bass, tenor, alto and soprano frequencies. The oscillators may be substantially identical in construction except for the values of their component elements, and each has its frequency determined by a tuned mesh in the grid circuit comprising a condenser C5 40 adapted to be connected in parallel with a greater or lesser portion of a tapped inductance L1. A winding L2 in the cathode circuit of the oscillator is inductively coupled to the inductance L1, and provides a means for feedback of energy to the grid circuit.

The outputs of the oscillators 84, 86, 88 and 90 45 are resistance and capacity coupled respectively with amplifier and volume control devices 94, 96, 98 and 100, and the outputs of these amplifiers 50 are supplied to the speakers 64, 66, 74 and 68 respectively.

Each of the keys A2⁸ to G4 is adapted to operate a single-pole double-throw switch 102, these 55 switches being normally in the upper position 60 illustrated, so as to be connected in series. The arrangement is such that the switch of the highest of a plurality of depressed keys effectively disconnects the switches of the lower keys from the circuit. Each of the switches 102 is adapted 65 upon depression to connect a predetermined number of turns of the inductance L1 in parallel with the condenser C5, and thereby determine the frequency of oscillation of the oscillator 90. Because of the series arrangement of the switches 102 it will be clear that the oscillator 90 will always be tuned to the frequency represented by the highest of a plurality of depressed keys, provided such key lies within the range A2⁸ to G4.

The switching system for tuning the alto oscil-

lator 88 is slightly more complicated since this oscillator must be tuned to the second highest of two or more keys depressed in the soprano-alto range, but if only one key within this range is depressed, the alto oscillator 88 must be tuned to the frequency of such depressed key. This switching mechanism comprises a single-pole double-throw switch 106 for each of the keys of the combined alto and soprano range G2 to G4, a second single-pole double-throw switch 108 for each of the keys of the alto range from G2 to D4, and a single-pole double-throw switch 110 as well as a single-pole single-throw switch 112 for each of the keys of the combined alto-soprano range from G2 to G4. The switches are shown in Fig. 2 in their normal positions in which case all of the switches 106 form a series connection between a terminal A and ground, thus shunting the condenser C5 to render the oscillator 88 ineffective.

The series of switches 108 are adapted to connect the terminal B to one of the taps on the inductance L4, which corresponds to the inductance L1. The series of switches 110, when no keys are depressed, connect the terminal A to the terminal B, while the series of switches 112 under similar conditions are in parallel with the series of switches 110 and likewise form a closed circuit between the terminals A and B.

It will be noted that the arrangement of the switches 106 and 108 is such that when a key is depressed, the operated switch 106 connects the series of switches 108 of pitch lower than the depressed key to the terminal A, and disconnects said lower switches from the terminal B.

In a somewhat similar manner the operation of but one of the keys will break both the circuits through the series of switches 110 and the series of switches 112, but will establish a connection between the switch 110 of the depressed key and the series of switches 112 higher than the depressed key. Thus, a circuit will be maintained between the terminals A and B when but one key within the range G2 to G4 is depressed. As a result, the switch 108 of the depressed key will complete a circuit from the terminal A through a portion of the winding L4, and thus tune the oscillator to the frequency represented by the depressed key. When but one key within the overlapping portion of the alto-soprano range is depressed, the alto and soprano oscillators will be tuned to the same frequency, and their speakers 68 and 74 will emit unison tones.

When, however, two keys respectively within the soprano and alto ranges are simultaneously depressed, the circuit through this series of switches 110 and the circuit through the series of switches 112 will each be broken at two places, and therefore the circuit between the terminals A and B will be broken. (For the sake of brevity the latter circuit will hereinafter be referred to as the "A-B" circuit.) The operation of the switch 108 associated with the highest of the two keys depressed will therefore not be effective to connect its associated inductance tap to the terminal A.

The depression of the higher of the two keys depressed will cause the connection of all the switches 108 of lower keys to the terminal A through the switch 106 of the depressed key and the switches 106 of keys higher than the highest key depressed. Since the switch 108 of the lower of two depressed keys is thus connected to the terminal A, its operation will effectively connect the tap of the winding L4 associated with it to the terminal A. Thus, the portion of the wind-

ing L4 necessary to tune the oscillator 88 to the frequency of the lower of two simultaneously depressed keys will be connected in parallel with the condenser C5, and the oscillator will operate at the frequency of the lower of the two depressed keys.

If three keys within the range G2 to G4 are simultaneously depressed, the A-B circuits will of course be opened, and the second highest of the depressed keys will result in tuning the oscillator 88 to the frequency represented by such second highest depressed key, and at the same time disconnect the remaining lower switches 108 from the terminal A so that depression of any lower key will not have any effect upon the tuning of the oscillator 88. The key operated switch circuits associated with the oscillator 88 effectively tune the oscillator to the frequency of the depressed key if only one key within the alto range G2 to D4 is depressed, and tune the oscillator to the frequency represented by the second highest of two or more depressed keys in the alto-soprano range, provided that such second highest of the depressed keys lies in the alto range.

Each of the keys C1 to D3 is adapted to operate a switch 114, these switches being single-pole double-throw switches adapted, when the key is depressed, to make contact with appropriate taps on inductive winding L6 and thereby connect a greater or lesser number of turns thereof in parallel with the tuning condenser C5 of the bass oscillator 84. The operation of the switches 114 in tuning the oscillator 84 is similar to the operation of the switches 102 in tuning the soprano oscillator 90, except that the switches 114 are so arranged in series that the switch 114 of the lowest key depressed causes the corresponding switches for all of the higher keys to be disconnected from the circuit. Thus, the bass oscillator 84 will always be tuned to the frequency represented by the lowest of a plurality of depressed keys provided such lowest key lies within the range C1 to D3. (In actual practice the bass oscillator will usually be tuned to a frequency one octave lower than that represented by the depressed key.)

Each of the keys C1 to F3# is adapted to operate a single-pole double-throw switch 116, a single-pole single-throw switch 118, a single-pole double-throw switch 120, and a single-pole double-throw switch 122. It will be noted, however, that the switches 122 for the keys C1 to A1 are omitted. The switches 122 are adapted, upon depression of their associated keys, to make contact with taps on an inductive winding L8 which serves as the tuning inductance for the tenor oscillator 86. The switches 116 normally connect a terminal C with a terminal D, and the switches 118, being in series parallel with the switches 116, likewise normally connect the terminals C and D, the circuits between C and D through the switches 116 and 118 being termed a C-D circuit, similar in function to the A-B circuit previously described. As a result of this switching arrangement for the keys C1 to F3#, the tenor oscillator will be tuned to the frequency represented by the second lowest of a plurality of keys within the range C1 to F3#, provided this second lowest note lies in the range from A1# to F3#. If only one key within the latter range is depressed, the tenor oscillator will be tuned to the frequency represented by such key.

From the foregoing it will be apparent that the tenor oscillator switching arrangement is similar to the corresponding arrangement for the

alto oscillator 88 except that it is effective on the second lowest of a plurality of depressed keys, while the alto arrangement is effective on the second highest key. In a similar way, the switching arrangement for the bass oscillator 84 corresponds to the switching arrangement for the soprano oscillator 90 except that it is effective to tune the bass oscillator to the frequency of the lowermost key depressed, while the soprano arrangement is such as to tune the oscillator to the highest of a plurality of depressed keys within its range.

Let us assume that the instrument is utilized in playing four part harmony including the chord B1, G2, D4 and G4. Under these circumstances the bass oscillator 84 will be tuned to the frequency of the note B1 due to the operation of its switch 114 in connecting an appropriate portion of the inductance L8 in the tuning circuit of the oscillator. Likewise, the key G4 will, by the operation of its switch 102, connect the appropriate portion of the inductance L1 in the tuning circuit of the oscillator 90 to tune it to the frequency of the note G4. The key G2 will operate the switches 116, 118, 120 and 122 associated therewith, and because of the arrangement of the series switches 116 and 118, the normally closed C—D circuit will be opened. As a result, the switch 122 for the key G2 will connect to the tap on the winding L8 necessary to tune the oscillator 86 to the note G2, this circuit being completed through the switch 122 for the key G2, and through the switch 120 for the key B1. Thus, the tenor oscillator 84 will oscillate at the frequency of the note B1, and the bass oscillator 86 will oscillate at the frequency of the note G2.

In a similar manner the alto oscillator 88 will be made to oscillate at the frequency of the note D4. Despite the fact that the A—B circuit will be open because of the operation of two pairs of switches 110 and 112, the switch 108 for the note D4 will be connected to the terminal A because of the operation of the switch 106 for the key G4. Consequently, each of the four oscillators will be tuned to the frequency of its corresponding note of the chord represented by the keys depressed, and the four parts of the harmony will emanate from their respective speakers 64, 66, 68 and 74.

The switching arrangement of Figure 2 will operate satisfactorily in the playing of most four part harmony selections, but presents some difficulties in the rendition of chords having three notes. The switching system, under these circumstances, will of course tune the soprano oscillator 90 to the frequency represented by the highest key depressed, and the lowermost of the keys depressed will properly tune the bass oscillator 84 to the required frequency, provided that the highest and lowest keys are within the soprano and bass ranges respectively. However, the intermediate of the three keys depressed may produce results not intended by the composer, depending upon the location of this intermediate note in the scale, and depending upon the pitch of the other notes simultaneously depressed. Furthermore, the system is somewhat complicated and expensive since, it will be noted, some of the keys operate as many as ten switches, most of these being double-throw switches.

In an instrument designed to produce the best musical results, it would probably also be desirable to provide additional switches for keying the amplifiers connected to the oscillators so that the tones would have the proper attack and decay

characteristics. Such additional switches would also make certain that the amplifiers would be rendered ineffective during the short intervals that the oscillators are having their frequencies of oscillation changed, thus preventing transmission to the speakers of the transients produced incidental to shifting the frequencies of the oscillators.

In the switching arrangement of Fig. 3, most of the complications of the circuits of Fig. 2 are avoided, and by the operation of a suitable switch the player may readily determine whether the tenor or alto speaker shall sound the intermediate note of a three note chord. It thus provides a way of overcoming at least one of the possible disadvantages of the arrangement of Fig. 2.

The arrangement of Fig. 3 employs oscillators 84, 86, 88 and 90 for the bass, tenor, alto and soprano voices respectively. These oscillators may be of the same design as those described with reference to Fig. 2, and are adapted to supply their signals (with suitable exceptions hereinafter to be pointed out) to amplifiers 94, 96, 98 and 100 respectively. The amplifiers are connected to supply signals to the speakers 64, 66, 74 and 68 respectively.

Representative keys C1, A1#, G2, A2#, D3, F3#, D4 and G4 are illustrated as operating switches for tuning the oscillators, it being understood that these keys are representative of a complete keyboard extending, for example, from the note C1 to the note G4. The keys A2# to G4 are adapted to operate single-pole double-throw switches 102 as previously described, to tune the soprano oscillator 90 to the frequency of the highest of a plurality of depressed keys within the soprano range. Similarly, the keys G2 to D4 within the alto range are adapted to operate switches 106, 108 as previously described, and to tune the alto oscillator 88 to the frequency represented by the second highest of a plurality of depressed keys within the combined alto-soprano range, providing that such second highest depressed key falls within the alto range. The keys D4# to G4 are each adapted to operate a switch 106 but do not of course have a switch 108.

Switches 114 operated by the keys C1 to D3 in the bass range of the instrument are adapted to tune the bass oscillator 84 to the frequency represented by the lowest depressed key within the bass range.

Switches 120 and 122 for each of the keys A1# to F3# in the tenor range of the instrument are adapted to tune the tenor oscillator 86 to the frequency of the second lowest of a plurality of depressed keys within the combined bass-tenor range, provided of course that such second lowest depressed key lies within the tenor range. It will be noted also that switches 122 are omitted for the keys C1 to A1.

As thus far described, the keying arrangement is substantially identical with that disclosed in Figure 2 except for the omission of the A—B and C—D circuits. Without the addition of other circuits, presently to be described, the depression of a key such as D3 would result in sounding a note of this pitch from the soprano speaker 68 and from the bass speaker 64, but the alto speaker 74 and the tenor speaker 66 would not have a signal supplied thereto. To remedy this possible defect, as well as others which will be mentioned hereinafter, a pair of polarized relays 130 and 131 are provided, these relays being adapted to operate switches 132 and 133 respectively. The

switch 132 is arranged to connect the output of soprano oscillator 90 to the amplifier 98 for the alto speaker when the switch is in its normal closed position as shown. Similarly, the switch 133 is adapted to connect the bass oscillator 84 to the tenor amplifier 96 when the switch is in its normal closed position.

The object of providing the polarized relays 130 and 131 is to cause both the bass and tenor speakers 64 and 66 to sound a unison note when but one key within both the tenor and bass ranges is depressed, and similarly, to cause both the soprano and alto speakers 68 and 74 to sound the same note when but one key within the range of both the soprano and alto ranges is depressed. However, if four keys, of four part harmony chords, are depressed, the relays 130 and 131 should be energized to open the switches 132 and 133, and further, if a three note chord with two keys within the bass-tenor range is played, either the relay 130 or the relay 131 should be energized to open its associated switch so that the intermediate note of the three note chord may be sounded by the alto or tenor speaker, as desired.

The means for accomplishing the foregoing results includes a single-pole single-throw switch 134 operated by each of the keys. Each of the switches 134 has one pole thereof connected by conductor 136 with one terminal of a source of current shown as a battery 138. The other poles of the switches 134 are connected by resistances R1 respectively, with a common conductor 140. The conductor 140 is permanently connected to the other terminal of the battery 138 through a resistor R2.

The windings of the relays 130 and 131 each have one terminal connected to a conductor 142 which is connected to the battery 138 at a point intermediate its end terminals. The other terminal of the winding for the relay 130 is connected to a conductor 144, while the other terminal of the winding for the relay 131 has a conductor 145 connected thereto. A resistor R3 connects the conductors 144 and 145, and a switch 146 is adapted to connect the conductor 140 either to conductor 144 or to conductor 145. The switch 146 may be manually operated by the player, being located on the console for operation either by the player's foot, knee, or by a hand operated tablet.

The values of the constants of the relay energizing circuits and the initial polarization of the relays 130 and 131 are such that the current flow upon depression of one of the keys, and hence closure of one of the switches 134, is insufficient to operate either of the relays 130 or 131. Likewise, the depression of even two keys, and hence the completion of circuits through two of the resistors R1, is insufficient to operate the relays 130 and 131.

However, when three keys are simultaneously depressed, the current flow through three parallel resistors R1, and hence through the switch 146 to the relays, will be sufficient to cause the energization of the relay to which the switch 146 is directly connected. With the switch 146 in the position shown in Fig. 3, the current flow upon depression of three keys would be sufficient to cause operation of the relay 131, but due to the interposition of the resistor R3 in the energizing circuit for the relay 130, the latter would not be supplied with sufficient current to cause it to operate.

However, upon depression of four or more keys, the current flow through the four or more par-

allel resistances R1 would be sufficient, irrespective of the position of the switch 146, to cause operation of both relays 130, 131, thus opening the switches 132 and 133.

As a result of these control circuits for the relays, it will be apparent that the apparatus will operate as follows:

(a) When one key is depressed within the range C1 to A2, the tenor oscillator 86 will not oscillate, since its condenser C5 will be shunted through the circuits of the switches 120 and 122. The bass oscillator 84 will be tuned to the frequency represented by the depressed key, its output being supplied to the bass amplifier 94 and speaker 64, and through the closed switch 133 to the tenor amplifier 96 and its speaker 66. Thus, the tone corresponding to the depressed key will emanate from both the bass and tenor speakers. Similarly, if but a single key within the range D3# to G4 is depressed, the soprano oscillator 90 is the only oscillator which will be tuned to the frequency corresponding to the depressed key, but the output of the soprano oscillator will be supplied to both the alto and soprano amplifiers 98 and 100 because of the fact that the amplifier 98 for the alto speaker will be connected to the output of the soprano oscillator through the closed switch 132. Likewise, if a single key within the range A2# to D3

is depressed, the soprano and bass oscillators 90 and 84 will be tuned to the frequencies represented by the depressed key and their outputs will be supplied respectively to the soprano-alto and bass-tenor amplifiers and speakers, since the relay switches 132 and 133 will be closed. Under the latter circumstances the alto and tenor oscillators 88 and 86 will be rendered inoperative due to the shunting of their condensers C5 by their respective switch circuits.

(b) The depression of two keys, depending upon their position in the gamut of the instrument, will cause the sounding of the lower note by the bass and tenor speakers, and the sounding of a higher note by the alto and soprano speakers. If both keys are above the key D3, the notes will sound respectively from the alto and soprano speakers, or if both are below the note A2# the notes will sound from the bass and tenor speakers respectively.

(c) Upon simultaneous depression of three keys of a chord, as is common in four part harmony music, the soprano oscillator 90 will be tuned to the frequency corresponding to the highest key and the bass oscillator 84 will be tuned to the lowest key. Depending upon the position of the switch 146 either both the alto and soprano amplifiers and speakers will be connected to the soprano oscillator, or both the tenor and bass amplifiers and speakers will be connected to the bass oscillator. By operating the switch 146 the player may determine whether the tone corresponding to the intermediate of the three keys depressed will not be sounded by the alto or by the tenor speaker. Upon depression of certain combinations of three keys it is possible that the alto and soprano amplifiers and speakers will both be connected to receive the outputs of both the alto and soprano oscillators. Similarly, upon depression of other combinations of three keys, both the bass and tenor amplifiers and speakers will be connected to receive signals from both the bass and tenor oscillators. However, such combinations will be rather unusual in four part harmony music, and the results stated will not be particularly dis-

advantageous since each singer will hear the tone which he is to sing. The only disadvantage will be the singer's possible confusion by hearing an additional note, other than the one he is to sing, from his particular speaker.

(d) When four keys are simultaneously depressed both of the relays 130 and 131 will be energized to open their switches 132 and 133 so that each amplifier and speaker will be supplied solely with the signal from its associated oscillator, and the tones of the four parts of the chord being played will be produced correctly by their respective speakers.

From the foregoing detailed analysis of the operation of the circuit of Fig. 3, it will be apparent that this circuit arrangement has advantages over the circuit arrangement of Fig. 2, particularly in the availability to the player of some control over the selection of the speakers which are to sound the unison note when but three keys are simultaneously depressed, and in the greater simplicity of the circuit as a whole. The circuit of Fig. 3, nevertheless, is comparatively complicated and might not be entirely faultless in practical operation because of possible variations in the operation of the relays, changes in the potential of the source 138, and also due to other possible variable factors.

Because of the complexity of any key operated switching system by which four part harmony may be rendered by playing upon the keyboard in a conventional manner, I prefer to utilize a relatively simple switching system which does not have the disadvantages of the arrangements shown in Figs. 2 and 3, but which requires of the player that he play the alto and soprano parts upon keys apparently an octave higher than as scored. While the keyboard and the technique required are thus not entirely conventional, the deviations from the conventional are so slight as to be inconsequential to the player.

The novel form of keyboard is shown in perspective in Fig. 4 comprising fifty-one keys bearing reference characters from 1 to 51 inclusive. The keyboard appears to be conventional except for a divider 180 which may be in the form of a rigid block between the keys 25 and 21, or may be in the form merely of a suitable marking on either of the keys 25 and 21, or upon both of these keys, or upon the key 26. As a matter of practical construction, such marking of the division of the keyboard is not essential and in practice may be omitted, since, except for a player using the instrument for the first time, such marking would have little or no utility. Each of the keys 1 to 51 also bears a designation of the pitch of the tone controlled thereby, and it will be noted that the keys 1 to 26 control production of tones F1 to F3 $\frac{1}{2}$ inclusive, while the keys 27 to 51 control the production of tones G2 to G4 inclusive respectively.

It will be noted that the octave from G2 to F3 $\frac{1}{2}$ is repeated. By virtue of this arrangement the left hand, by depressing selected keys of the left hand group 1 to 26, may be utilized to play the tenor and bass parts, while the right hand, by playing on the keys 27 to 51, inclusive, may control the rendition of the soprano and alto parts. In playing four part harmony upon the instrument the player merely depresses keys apparently an octave higher than normal with the fingers of his right hand. In other respects the music is played exactly as scored.

The key operated switching mechanism by which these improved results may be obtained is

shown in Fig. 5 wherein each of the keys 30 to 51 is shown as capable of operating a single-pole double-throw switch 182 which, in a manner similar to that described with reference to Fig. 2, is adapted to determine the frequency of oscillation of the soprano oscillator 90, the highest of a plurality of depressed keys within this range determining the frequency of oscillation.

Each of the keys 21 to 46 is adapted to operate a single-pole double-throw switch 184, these switches being connected in series in such manner that the lowest of a plurality of these switches operated will be effective in tuning the alto oscillator 88. Except for the arrangement of the switching mechanism, the soprano and alto oscillators 90 and 88 may be identical with the corresponding oscillators described with reference to Fig. 2, and the same reference characters have therefore been utilized to designate the corresponding parts.

The bass oscillator 88 has a key switching arrangement substantially identical with that shown in Fig. 2, each of the keys 1 to 21 being adapted to operate a single-pole double-throw switch 186, the switches being connected in series arrangement such that the lowermost of a plurality of depressed keys within the bass range will determine the frequency of oscillation of the bass oscillator 84.

Each of the keys 6 to 26 inclusive is adapted to operate a single-pole double-throw switch 188, these switches being connected in series in such manner that the highest of the depressed keys within this range which will determine the frequency of oscillation of the alto oscillator 86.

From a comparison of the switching arrangement of Fig. 5 with those of Figs. 2 and 3, the greater simplicity of the arrangement of Fig. 5 will become readily apparent. The arrangement of Fig. 5 has the pronounced advantage that the musician may play the selection as scored (with the exception of the octave displacement of the right hand), and each of the harmony parts will automatically and without fail be produced by the oscillator and speaker for that part, irrespective of the unison notes. The only possible condition, which is very rare in four part harmony, under which the switching arrangement of Fig. 5 could not be used in following exactly the score as written, would be when one of the parts rests. Under these circumstances the player would merely have to adjust the volume control for the part in which the rest occurs to a zero value in order to render the desired speaker ineffective.

As shown in Fig. 4, a plurality of tablets 160 may be provided adjacent the keyboard, these tablets being adjustable individually to control the volumes of the outputs of the various speakers. In addition, such tablets may be utilized to control to a limited extent the variation of tone qualities of the various speakers by inserting and removing suitable filtering meshes in the amplifier circuits. The amplifiers and speakers are preferably arranged so that each speaker will deliver a tone differing slightly in quality from the tones supplied by the other speakers, thus further aiding the singers in following their particular parts, and improving the over-all quality of the music produced by the instrument.

By virtue of the fact that each oscillator operates throughout but a limited frequency range, the oscillators, as well as their amplifiers and speakers, may be selected and designed for their particular frequency ranges, with consequent im-

proved efficiency and tonal output, and with corresponding suppression or attenuation of spurious frequencies lying without their respective frequency ranges. Since each speaker emits but one tone at a time, harmonic distortion is not particularly disadvantageous, and, in fact, may improve the tone quality.

In using the instrument employing any one of the three forms of key switching arrangements disclosed, a single player at a single console may play four part harmony music, and within the limitations previously noted as to some forms of the invention, the tones of each of the four parts will emanate from their respective speakers. The singers grouped about the speakers for their respective parts will thus be cued to sing their parts, with the result that it will be possible for relatively inexperienced singers to follow their respective parts with little or no rehearsal. Thus, quartets, choirs and even whole congregations may very easily and correctly sing four part harmony with consequent pleasure and satisfaction to the singers and listeners.

In accordance with the principles of the invention disclosed and claimed in my co-pending application Serial No. 347,265, filed July 24, 1940, a bass pedal operated by the player of the instrument may be provided to render the bass oscillator effective, or to cause this oscillator, or an additional oscillator, to produce a tone one octave lower than the nominal frequency of the lowest depressed key.

Furthermore, the various volume controls of the outputs of the four oscillators may be controlled by a common pedal or other control operated by the player, as well as being capable of having their volumes individually controlled by operation of the tablets 180.

It will be understood that the particular form of oscillators disclosed are merely representative of any suitable oscillatory audio frequency generating systems, or other tone producing devices capable of being electrically controlled by means of key operated switches. The specific forms of the switching arrangements are not claimed herein, the embodiment shown in Figs. 4 and 5 forming the subject matter of co-pending application Serial No. 387,114, filed April 7, 1941.

The claims of this application are drawn to the broad principle of providing a separate musical tone producing apparatus for each of a plurality of harmony parts, and physically spaced relatively far apart, but controlled from a common console in such manner that a musician may play multi-part harmony on the console, and each tone producing apparatus will produce the tones corresponding to its part as played at the console.

It will be apparent to those skilled in the art that numerous modifications and variations in the form of the apparatus may be made without departing from the fundamental principles of the invention. I therefore desire to include within the scope of the following claims, all such

modifications and variations by which substantially the results of the invention may be obtained in substantially the same or in a similar manner.

5 I claim:

1. In an electrical musical instrument of the keyboard type especially adapted for instruction in multi-part harmony singing, a keyboard comprising a plurality of keys arranged in the normal note sequence for more than an octave, a plurality of separate melody instruments each capable of playing at one time only one note or notes in octave relationship, a separate speaker for each of said instruments, connections for operating said speakers simultaneously at points sufficiently remote from one another to afford localized sound sources for individual groups of singers, a plurality of electric switches operated by each key of said keyboard, said switches being connected for operating a plurality of said melody instruments in unison and on the same note when only one key is depressed but on separate harmony notes when a plurality of keys are simultaneously depressed within the same octave.
- 10 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870
2. An electrically controlled musical instrument especially adapted for the accompaniment of multi-part harmony singing, comprising a plurality of musical tone producing units in number at least equal to the number of singing parts to be accompanied, said units being capable respectively of producing musical tones extending throughout the ranges of their related singing parts, a single console having keys easily playable by one player in the rendition of all of the notes of a multi-part harmony singing score, and a plurality of electrical circuits including switches operated by the keys of said console to cause the sounding of one of said units of a tone corresponding to the highest pitched key of a plurality of said keys depressed at one time, and to cause the sounding by another of said units of a tone corresponding to one of the other of such depressed keys.
3. The combination set forth in claim 2 in which said units include sound emitting parts, and in which the sound emitting parts of the different units are separated sufficiently far apart to enable persons in their vicinity to identify the source of tones emanating from one of said units when at least two of said units are producing musical tones at the same time.
4. The combination set forth in claim 2 in which means are provided separately to control the volume of the acoustic output of each of the units.
5. The combination set forth in claim 2 in which each of the units produces tones of quality differing from that of the tones of the unit of nearest pitch range.

LAURENS HAMMOND.
